US0D1077433S

(12) United States Design Patent (10) Patent No.: US D1,077,433 S
Matthews (45) Date of Patent: * Jun. 3, 2025

(54) SHOE

(71) Applicant: NIKE, Inc., Beaverton, OR (US)

(72) Inventor: Darryl Matthews, Portland, OR (US)

(73) Assignee: NIKE, Inc., Beaverton, OR (US)

() Term: 15 Years

(21) Appl. No.: 29/886,976

(22) Filed: Mar. 15, 2023

(51) LOC (15) Cl. 02-04

(52) U.S. Cl. USPC D2/947; D2/902

(58) Field of Classification Search
USPC D2/902, 907, 908, 946, 947, 948, 951, D2/896

(57) CLAIM

The ornamental design for a shoe as shown and described.

DESCRIPTION

FIG. 1 is a front perspective view of a shoe showing my new design;

FIG. 2 is a side view thereof; and,

FIG. 3 is a rear perspective view thereof.

The broken lines depicting the remainder of the shoe form no part of the claimed design.

1 Claim, 3 Drawing Sheets
